DESIGN FOR A STOOL

Homer G. Kellogg, Highland Park, Mich.

Application March 20, 1939, Serial No. 83,717

Term of patent 14 years

To all whom it may concern:

Be it known that I, Homer G. Kellogg, a citizen of the United States of America, residing at Highland Park, in the county of Wayne and State of Michigan, have invented a new, original, and ornamental Design for a Stool, of which the following is a specification, reference being had therein to the accompanying drawing, forming a part thereof, wherein

I claim:

The ornamental design for a stool, substantially as shown.

HOMER G. KELLOGG.
